UNITED STATES PATENT OFFICE.

HENRY C. RIESBOL, OF NEW YORK, N. Y.

CONCRETE BUILDING FORM.

Application filed February 25, 1925. Serial No. 11,596.

To all whom it may concern:

Be it known that I, HENRY C. RIESBOL, a citizen of United States, residing at New York city, in the county of New York and 5 State of New York, have invented new and useful Improvements in Concrete Building Forms, of which the following is a specification.

This invention relates to improvements 10 in concrete building forms and is an improvement over the form of my invention shown and described in my co-pending application Sr. No. 750,410, filed November 17th, 1924.

15 The principal object of the invention resides in the construction of a concrete form for use in "pouring" the outer wall of a building and which may be reversed and utilized for the "pouring" of the inner wall 20 when forming a double wall structure having an air space between the walls.

Other objects of the invention are to provide a cheap and inexpensive form for the 25 construction of hollow reinforced concrete walls; to eliminate the high labor costs in the assembling of the form and to pour a one story double wall in two operations.

A further object is the provision of a 30 single form for the pouring first of the outer ribbed wall, and which is rearranged in position for receiving the pouring of the inner wall, there being a novel means for supporting the form sections in spaced relation with the outer wall during the pouring 35 of the inner wall.

With these and other objects in view, the 40 invention resides in certain novel construction and combination and arrangement of parts, the essential features of which are hereinafter fully described, are particularly pointed out in the appended claims, and are illustrated in the accompanying drawing, in which:—

Figure 1 is a horizontal sectional view 45 showing the manner of forming the outer wall of a building.

Figure 2 is a similar view but showing the form section in position for forming the inner wall.

50 Figure 3 is a horizontal sectional view through a portion of the complete wall structure.

Figure 4 is an enlarged detail sectional view illustrating the means for holding the

inner form sections in sealing engagement 55 with the ribs of the outer wall.

Figure 5 is a perspective view of one of the inner form sections.

Figure 6 is a perspective view of the wall spacer.

Figure 7 is a detail perspective view of the bond structure between outer and inner walls.

Referring more particularly to the drawing, the reference numeral 10 designates a metallic channel member which is U-shaped in horizontal section and which is formed with outwardly extending flanges 11. Any number of channel members may be employed in the construction of a wall, the 60 amount depending upon the length of the wall and the distance desired between the ribs which are to be formed on the wall. In use, the members are placed upright in a vertical position and held therein by a 65 form 12 into which the concrete is poured.

The form 12 comprises an outer section 13 and an inner section 14 which are held in spaced relation by brace rods 15. The outer section 13 includes a horizontal liner 16 any 70 number of which may be provided and arranged in spaced relation and which engage vertical beams 17 carried by the wall forming sections 18. The sections 18 are arranged in intimate contact with each other to form 75 the outer wall of a mold cavity 19 formed by the space between the outer and inner sections 13 and 14.

The inner section 14 includes a plurality 80 of inner wall forming sections 20 between the meeting edges of which one of the channel members 10 is arranged. The ends of the sections 20 about the flanges 11 which prevent movement of the sections toward the outer section 13. The sections 20 are held in position by a horizontal liner 21 which is supported by brackets 22' carried by the channel members 10. Any number of these liners may be employed, but for the ordinary height wall, three have been found to 85 be sufficient. The liners 16 and 21 are held tight against the inner and outer wall forms by wires 22 which are looped about the liners and fastened securely as at 23 for a distance 90 approximating the thickness of the wall to 95 be formed.

Additional means is provided for holding the outer sections 18 in vertical position

which includes bolts 24 which extend through openings 25 in the body portion of the channel members and which extend into the cavity 19. The bolts are inserted at suitable points along the length of the channel member and each receives a nut 26 upon its threaded end. Each nut is formed with an eye 27 to which the free ends of a wire 28 are connected, the wires extending through the outer wall sections and around the meeting beams 17.

When removing the form after the formation of the outer wall, the wires 22 and 28 are clipped adjacent the surface of the wall to permit the liners 16 and 21 to be removed, after which the bolts 24 are unscrewed from the nuts 26, thereby leaving the nuts and bolts of the wires 28 in the wall structure. This now leaves the channel members free whereby the wall is clear of any form structure, it being understood that the outer wall forming sections 18 have been previously removed with the liners 16 after the severing of the wires 22 and 28.

Figure 2 of the drawing clearly shows the outer wall structure in its completed condition wherein it will be noted that the brace rods 15, the twisted portions 23, portions of the wire 28 and the nuts 26 are left in the wall for adding strength of the same and the saving of time in the removal of the form. It will be seen that the channel members serve to form spaced ribs 29 on the inner surface of the outer wall designated by the numeral A.

Rods 30 are anchored in the wall during the pouring of the same and extend through and beyond the ribs 29 to provide a bond between the outer and inner wall about to be described. Before forming the inner wall, the outer face of the ribs is provided with water proofing material for preventing condensation on the face of the inner wall.

From the foregoing description it will be seen that the outer wall has been formed at which time the sealing strips 31 are attached to the vertical beams of the sections 20 by means of spring clips 32 carried at spaced intervals upon the length of said strip, and the sections in turn placed in alignment with the outer face of the ribs. The strips are formed of sheets of rubber bent upon themselves and secured to provide yieldable portions for closing the space between the sections and the ribs and which are wedged therebetween for frictionally supporting said sections in set up position.

Spacers 33 are interposed between each section 20 and the outer wall and each is formed with spaced parallel rails 34 connected by blocks 35 rotatably mounted thereon. These spacers serve to brace the sections 20 during the pouring of the inner wall.

The sections 18 previously employed for

pouring the exterior surface of the outer wall are now placed in position and are held spaced by the rods 30 and spacers 36.

The meeting beams 17 receive clips 37 at spaced intervals for retaining the sections in tight contact and passing through each clip 37 is a bolt 38 which is threaded into the nut 26 anchored in the outer wall and which formerly coated with the bolt 24 for holding the channel bars in position during the formation of the outer wall. The form sections are now in position for receiving the "pouring" of the inner wall which joins the ribs of the outer wall and which is bonded by the rods 30.

After the outer wall has been poured and dried, the spacers 33 are removed by inserting an implement to rotate or destroy the blocks 35 to move them to a position parallel to the rails 34 which permits their easy removal. The outer sections 18 are now removed by disengaging the bolt 38 from the nut 26 and by removing the clips 37. The sections 20 are now free to be drawn upwardly from the air spaces 40 between the outer wall A and the inner wall B.

The inner wall B is also reinforced by reinforcing rods 41 similar to the rods 31 in the outer wall. When the forms have all been removed, a wall such as shown in Figure 3 is provided and which is poured one story high at a "pouring" thereby greatly reducing the labor costs and the use of expensive forms now employed for the formation of a double wall structure.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:

1. A building form adapted to be used in combination with a solid wall structure having spaced vertical ribs, including inner and outer sections, means for supporting said inner sections in spaced relation to the interior surface of said solid wall structure between said ribs, and means for supporting said outer sections in spaced relation to said inner sections to form a cavity therebetween.

2. A building form adapted to be used in combination with a solid wall structure having spaced vertical ribs, including inner and outer sections, means for spacing said inner sections from the interior surface of said solid wall structure, said inner sections disposed between said ribs, sealing and supporting means carried by said inner sec-

tions for engagement with said ribs, and means for supporting said outer sections in spaced relation to said inner sections to form a cavity therebetween.

6. 3. A building form adapted to be used in combination with a solid wall structure having spaced vertical ribs, including inner and outer sections, removable spacer members between said inner sections and said wall structure, yieldable members carried by the vertical sides of said sections for co-action with said ribs to seal the joint therebetween, and means for supporting said outer sections in spaced relation to said inner sections to form a cavity therebetween.

4. A building form adapted for use in forming a double wall structure, the combination with the outer wall thereof having spaced ribs on the inner side thereof, a plurality of inner sections, means for supporting said inner sections in spaced relation with said outer wall and between said ribs, a plurality of outer sections, means for spacing said outer sections from said inner sections, and means for holding said outer sections in set up position.

5. A building form adapted for use in forming a double wall structure, the combination with the outer wall thereof having spaced ribs on the inner side thereof, a plurality of inner sections, means for supporting said inner sections in spaced relation with said outer wall and between said ribs, a plurality of outer sections, means for spacing said outer sections from said inner sections, and means for holding said outer sections in set up position, said last means including elements anchored in the ribs of said outer wall and members pass-

ing through said outer sections for co-action with the respective elements.

6. A building form adapted for use in forming a double wall structure, the combination with the outer wall thereof having spaced ribs on the inner side thereof, a plurality of inner sections, means for supporting said inner sections in spaced relation with said outer wall and between said ribs, a plurality of outer sections, means for spacing said outer sections from said inner sections, and means for holding said outer sections in set-up position, said last means including elements anchored in the ribs of said outer wall, clips co-acting with the meeting ends of said outer sections, and members passing through said outer section and said clips for co-action with the respective elements.

7. A building form adapted for use in combination with a wall having spaced ribs extending from one side thereof, a form section, and removable means carried by the vertical sides of said section for co-action with said ribs for sealing the joint therebetween.

8. A form section for use in the construction of walls comprising spaced vertical beams, a plate connecting said beams, and yieldable strips carried by said beams and extending the length of the same.

9. A form section for use in the construction of walls comprising spaced vertical beams, cross pieces connecting said beams, and yieldable strips removably carried by said beams and extending the length of the same.

In testimony whereof I have affixed my signature.

HENRY C. RIESBOL.
